COMBINED IONIZATION CHAMBER, ION ACCELERATOR, AXIALLY ALIGNED ION PUMP AND TARGET FOR A NEUTRON GENERATING APPARATUS

Barney J. Carr, Colorado Springs, Colo., assignor to
Kaman Aircraft Corporation, a corporation of
Connecticut

Filed Oct. 19, 1962, Ser. No. 72,192

Term of patent 14 years

(Cl. D26—1)

FIG. 1.

FIG. 2.

FIG. 3.

FIG. 4.

FIGURE 1 is a top plan view of a combined ionization chamber, ion accelerator, axially aligned ion pump and target for a neutron generating apparatus showing my new design, the bottom being substantially a mirror image thereof;

FIGURE 2 is a front elevational view, the rear being substantially a mirror image thereof;

FIGURE 3 is an end view of one end thereof; and,

FIGURE 4 is an end view of the other end.

I claim:

The ornamental design for a combined ionization chamber, ion accelerator, axially aligned ion pump and target for a neutron generating apparatus as shown and described.
